LOADERS

David Gustavsson, Orebro, Sweden, assignor to Atlas Copco Aktiebolag, Nacka, Sweden, a corporation of Sweden

Application April 14, 1952, Serial No. 282,222

Claims priority, application Sweden April 16, 1951

7 Claims. (Cl. 214—132)

This invention relates to loaders of the type comprising in combination a base, a superstructure mounted to swing horizontally on said base, a shovel carried by said superstructure and movable on the superstructure from a loading position into a discharge position, and means for swinging the superstructure horizontally on the base. Such loaders are conventional in mines and tunnels and other working places with restricted head room for loading ore or rock or the like in mine cars or the like. The base of these loaders is usually provided with wheels adapted to run on rails laid on the mine floor. Furthermore, the base is usually provided with a traction motor connected to one or both pairs of wheels. Said motor is often a reversible compressed air driven motor but electric or internal combustion motors are also used. Furthermore, a second motor is usually provided on the superstructure for moving the shovel from loading or digging position to discharge position.

In loaders of the above described and similar well known types it has been suggested to provide pressure fluid cylinders for swinging the superstructure and shovel horizontally on the base.

One object of this invention is to provide improved means for such horizontal swinging which permit the operator of the loader in a simple way to swing the superstructure and shovel horizontally from lateral loading or digging positions into a position in a plane such as the longitudinal centre plane of the loader, in which the discharge of the shovel takes place, as well as to swing the superstructure and shovel laterally into any desired lateral position in which the filling of the shovel or the digging operation takes place. A further object of the invention is to provide means for automatically swinging the superstructure and shovel horizontally into said centre or other discharge position during the motion of the shovel from the filling or digging position to the discharge position. A still further object of the invention is to provide horizontal swinging means for the superstructure and shovel which are simple in manufacture and maintenance and which are of a rugged design fit for loaders of the above type. For these and other purposes I provide in a loader of the type described at least one pressure fluid cylinder and piston operable to swing the superstructure on the base horizontally from a lateral position towards a centre position or the like, and at least one further pressure fluid cylinder and piston in said loader operable to swing the superstructure on the base horizontally from said centre position or the like into a lateral filling or digging position.

In the accompanying drawings one embodiment of a loader according to the invention and a modification thereof are illustrated by way of example. Fig. 1 is a side view of a loader in which portions of the shovel and a side wall of the superstructure are broken away. Fig. 2 is a horizontal section substantially on line II—II of Fig. 1 on a larger scale. Fig. 3 illustrates on a still larger scale details of a valve mechanism for automatically centering the superstructure and the shovel. Fig. 4 is a side view

2

of a loader showing a modification of the loader illustrated in Fig. 1. Figs. 5 and 6 illustrate on a larger scale details of the automatic centering mechanism of the loader according to Fig. 4. Figs. 7, 8 and 9 illustrate a valve mechanism forming a part of the loader according to Figs. 1 and 2.

The loader illustrated in Figs. 1-3 and 7-9 consists of a movable base 1 on which a superstructure 2 is mounted on ball bearings 3 so that the superstructure may be swung horizontally from a centre position into various lateral positions and vice versa. The superstructure 2 comprises a turn table 65 provided with two rails 4 on which two rockers forming a rocker structure 5 carrying a shovel 6 may produce a rolling movement during the motion of the shovel from the low loading or digging position illustrated in Fig. 1 to an elevated discharge position (not illustrated) at the opposite end of the loader. The means for producing this rolling motion have not been illustrated in the drawing since they are well known in connection with loaders of this type which are used in mines and in tunneling operations in rock for loading material from the floor to a car.

Two compressed air operated cylinders 7 and 8 are provided in the base 1 as is obvious from Figs. 1 and 2. The cylinder 7 contains a piston 9 which is double-acting and connected by means of a piston rod 10 and a link 11 to a plate 12 rigidly secured to a hub 66 attached to the bottom of the superstructure 2. Consequently, the plate 12 always moves together with the superstructure. The supply and discharge, respectively, of pressure fluid such as compressed air, to and from the cylinder 7 is controlled by a valve disposed in a valve casing 13 provided on the base 1. The valve casing 13 has provided therein a piston valve 14 (Fig. 7) which is reciprocable against the action of a spring 15 and carries a roller 16 which cooperates with a cam 67 provided on the turntable 65 of the superstructure 2. The valve casing 13 has passages 17 and 18 connected through conduits 19 and 20 with spaces 26 and 27, respectively, on the opposite sides of the piston 9 in the cylinder 7. The valve casing 13 is furthermore provided with passages 21, 22, 23 of which the passages 21 and 23 are open to the atmosphere whereas the passage 22 is connected through a pipe 28 to a control valve casing 29 provided on one of the side walls 50 of the superstructure 2. The pipe 28 is partially a flexible pipe which permits movement of the superstructure 2 relative to the base 1. The control valve casing 29 is connected through a pipe 30 to a conduit 31 to which compressed air is supplied to the loader from a compressed air system. The valve device 29 is illustrated on a larger scale in Fig. 3. A bell crank lever 32 is mounted on the superstructure 2 in such a manner that it is situated in the path of the rocker structure 5. The bell crank lever is fixed on a shaft 33 which is journaled in the superstructure and carries a lever 34 cooperating in a certain position of the bell crank lever to lift a lever 35 which is also journaled on the superstructure 2 by means of a trunnion 69. A valve member 36 bears on the lever 35 with a roller 70 and is movable in the valve casing 29 from a position in which it closes the communication between the conduits 30 and 28 and simultaneously opens a communication between the conduit 28 and the atmosphere to a position in which the valve member opens the communication between the conduits 30 and 28 and closes the communication from the conduit 28 to the atmosphere.

When the rocker structure during the movement of the shovel 6 from loading or digging position to discharge position rolls along the rails 4 and passes the bell crank lever 32 said lever is swung from the position illustrated in Fig. 1 to the position illustrated in Fig. 3 in which compressed air is admitted from the conduit 31 through

the conduit 30, the valve housing 29, the conduit 28 to the valve casing 13. If the valve member 14 is then in the position illustrated in Figs. 2 and 7, i. e. if the shovel and the superstructure are aligned in the longitudinal centre plane of the loader, then the roller 16 bears on a portion 71 of the cam 67 and the valve member 14 is in the position illustrated in Fig. 7. Compressed air is then not admitted to the cylinder spaces 26 or 27 of the cylinder 7 which are both vented to the atmosphere through the passages 21 and 23 as is obvious from Fig. 7. However, if the shovel and the superstructure 2 at the beginning of the shovel movement was swung laterally so that the roller 16 bore against the portion 72 or 73 of the cam 67, then compressed air would have been supplied to the valve casing 13 from the passage 22 to the passage 17 or 18 and cylinder chamber 26 or 27, respectively. The piston 9 then moves in a direction to swing the superstructure 2 to centre position in which the roller 16 bears again on the portion 71 of the cam 67 and the air in the cylinder 7 is again vented to the atmosphere and the supply of compressed air to the passage 22 is interrupted.

On the base 1 a small cylinder 37 with vertical axis is also provided, said cylinder communicating through a conduit 38 with the conduit 28 so that compressed air is always admitted to the cylinder 37 as soon as compressed air is admitted to the conduit 28. The cylinder 37 contains a piston 39 displaceable by air pressure in the cylinder against the action of a spring and having a piston rod 40 which tends to project from the base towards the bottom 65 of the superstructure 2. Said bottom has a corresponding recess 41 which the piston rod 40 may enter as soon as it registers with the recess and the shovel is in centered position. When the shovel is swung from any lateral position to the centre position by means of the piston 9 the piston rod 40 is always ready to enter the recess 41 as soon as the superstructure and the shovel have reached centre position. Upon entering the recess the piston rod locks the superstructure 2 relative to the base 1 in said centered position.

The cylinder 8 which is also disposed in the base serves to swing the superstructure 2 and shovel 6 laterally from centre position. Said cylinder contains a piston 42 which by means of a piston rod 43 and a link 44 is connected with the plate 12. The cylinder spaces 45 and 46 of the cylinder 8 are connected through conduits 47 and 48 with a valve casing 49 the valve member of which (not illustrated in the drawing) is manipulated by means of a lever 50. This valve may be made so that compressed air is supplied to one or the other of the cylinder spaces 45 or 46, respectively, when the lever 50 is tilted towards or away from the side wall 68 of the superstructure 2. Numeral 51 in Fig. 1 indicates a valve casing containing means for controlling the traction engine of the loader and 52 indicates a valve casing containing means for controlling the rocking motion of the shovel and rocker structure 5, 6 along the rails 4 on the superstructure. A lever 53 serves to control the rocker motion and the lever 50 may be arranged to control the traction engine and simultaneously the lateral swinging of the superstructure.

The modification of the invention illustrated in Figs. 4-6 is substantially the same as the embodiment according to Figs. 1-3 and the equivalent parts of the two embodiments have therefore been designated with the same reference numerals and are not described again. The difference between the two embodiments consists in the means for automatically centering the superstructure relative to the base under the control of the rocking motion of the shovel. For this purpose one side wall 54 of the superstructure carries two double armed levers 55, 56 which are mounted to swing so as to take a position in which they are in the path of the rocker structure 5 when said structure moves the shovel from discharge position to loading position, as indicated in connection with the lever 56 in Figs. 5 and 6, and, furthermore, a

position in which the rocker structure 5 may pass the levers without catching them, said position being taken by the lever 55 in Figs. 5 and 6. Coil springs 57 and 58 are provided for moving the levers to the last-mentioned position. A rod 60 is movable in its longitudinal direction in brackets 59 disposed on the side wall 54. Said rod is provided with pins 61 and 62 which cooperate respectively with the levers 55 and 56. The roller 70 of the valve member 36 bears on the rod 60 having a recess 63 which the roller enters when the rod is displaced to the right in Figs. 5 and 6 and the shovel is in loading or digging position.

When the rocker structure 5 moves the shovel from loading position to discharge position the rocker pushes the lever 55 to the positions illustrated in Figs. 5 and 6. The rod 60 then takes the position illustrated in Figs. 5 and 6 and compressed air from the conduit 31 is admitted through the conduit 30, the valve casing 29, the conduit 28 to the valve casing 13. Centering of the superstructure 2 is then produced in the same manner as described in connection with Figs. 1-4 and 7-9.

The loaders above described and illustrated in the drawings should be considered only as examples and may be modified in various different ways within the scope of the claims. For instance, instead of compressed air other pressure fluids, such as pressure liquid, may be used for producing the centering or lateral swinging motion of the superstructure on the loader base. The mechanisms for automatically centering the superstructure and shovel may sometimes be dispensed with and replaced by a valve mechanism controlled by the operator at his will.

What I claim is:

1. A loader comprising in combination a base, a superstructure swingable horizontally on said base, a shovel carried by said superstructure and movable on the superstructure from a lateral loading or digging position to a central discharge position, a centering pressure fluid cylinder and piston in said loader operable to swing the superstructure on the base horizontally from any lateral position within an arc of approximately 90° to either side of said central position towards said central position, and an additional pressure fluid cylinder and piston in said loader operable separately from said centering cylinder and piston to swing the superstructure on the base horizontally into lateral loading or digging position.

2. A loader as defined in claim 1 in which the pressure fluid supply to the centering cylinder is admitted under control of means movable from an inoperative position to a centering position in response to the movement of the shovel from loading position to discharge position.

3. A loader as defined in claim 1 in which the centering cylinder is double-acting, one cylinder end operating to center the superstructure from lateral positions at one side of said central position and the other from lateral positions at the opposite side of said central position, and in which a selecting distributor valve is provided for automatically conducting pressure fluid to the cylinder end of the side of the centering piston which produces centering motion from the position just taken by the superstructure.

4. A loader comprising in combination a movable base, a superstructure swingable horizontally on said base, a shovel, a rocker structure carrying said shovel and movable on said superstructure to carry the shovel from a digging and load receiving position at one side of the superstructure over the base to a load discharge position at the opposite side of the superstructure, a double acting pressure fluid centering cylinder connected to the superstructure and the base for swinging said superstructure relative to said base from various lateral positions toward a center position, means for supplying pressure fluid to said centering cylinder for effecting such swinging, an additional double acting pressure fluid cylinder operable independently of the centering cylinder and

connected to the superstructure and the base for swinging said superstructure relative to said base from a center position to various lateral positions, and a manually operable valve mechanism for supplying pressure fluid to one end or the other of said additional cylinder for controlling horizontal swinging caused in one direction or other other by said cylinder.

5. A loader comprising a mobile base, a superstructure mounted to turn in a horizontal plane on said base to lateral positions at either side of a center position, a loading element, a rocker structure carrying said element and movably mounted on said superstructure to swing said element in a vertical plane between loading and discharge positions, a power cylinder and piston operatively connected between said base and said superstructure for turning the latter from any of its lateral positions to said center position, means for admitting pressure fluid to said cylinder to actuate said piston, said means including a control valve responsive to the position of said superstructure for admitting fluid to the cylinder to cause the superstructure to be moved from any lateral position to said center position and to vent the cylinder when the latter position is reached, and separate means

operable independently of said cylinder for turning said superstructure from said center position to selected lateral positions on either side of said center position.

6. A loader as defined in claim 5 including fluid pressure actuated locking means for holding said superstructure in said center position and means for supplying pressure fluid to said locking means to activate the same only when pressure fluid is admitted to said control valve.

7. A loader as defined in claim 5 including valve means 10 operable in response to movement of said rocker structure toward said discharge position from loading position for admitting pressure fluid to said control valve, whereby to initiate movement of the structure toward said center position concomitantly with movement of the loading element to discharge position.
